US0D1048869S

(12) **United States Design Patent** (10) **Patent No.:** **US D1,048,869 S**
(45) **Date of Patent:** **** Oct. 29, 2024**

(54) **ADHESIVE ANCHOR PLATE**

(71) Applicant: **Simple Living Solutions, LLC**,
Scottsdale, AZ (US)

(72) Inventor: **Jamie Limber**, Phoenix, AZ (US)

(73) Assignee: **Simple Living Solutions, LLC**,
Scottsdale, AZ (US)

(**) Term: **15 Years**

(21) Appl. No.: **29/861,473**

(22) Filed: **Nov. 30, 2022**

(51) LOC (14) Cl. **08-11**

(52) U.S. Cl.

USPC **D8/367**

(58) **Field of Classification Search**

USPC D8/363, 367, 373, 372, 371, 354;
D6/323

CPC F16B 45/00; F16B 45/005; F16B 45/008;
F16B 45/012; F16B 45/15

(57) **CLAIM**

The ornamental design for an adhesive anchor plate, as shown and described.

DESCRIPTION

FIG. 1 is a perspective view of an adhesive anchor plate;
FIG. 2 is a front view of the adhesive anchor plate;
FIG. 3 is a rear view of the adhesive anchor plate;
FIG. 4 is a bottom view of the adhesive anchor plate;
FIG. 5 is a top view of the adhesive anchor plate;
FIG. 6 is a left side view of the adhesive anchor plate;
FIG. 7 is a right side view of the adhesive anchor plate;
FIG. 8 is a perspective view of an alternative embodiment of the adhesive anchor plate;
FIG. 9 is a front view of the alternative embodiment of the adhesive anchor plate;
FIG. 10 is a rear view of the alternative embodiment of the adhesive anchor plate;
FIG. 11 is a bottom view of the alternative embodiment of the adhesive anchor plate;
FIG. 12 is a top view of the alternative embodiment of the adhesive anchor plate;
FIG. 13 is a left side view of the alternative embodiment of the adhesive anchor plate; and,
FIG. 14 is a right side view of the alternative embodiment of the adhesive anchor plate.
